UNITED STATES PATENT OFFICE.

EDWARD CLIFF, OF NEWARK, NEW JERSEY, ASSIGNOR TO THE CLIFF & GUIBERT COMPANY, OF NEW YORK, N. Y.

DESIGN FOR AN END DISK FOR HOSE-REELS.

SPECIFICATION forming part of Design No. 32,338, dated March 13, 1900.

Application filed February 12, 1900. Serial No. 5,016. Term of patent 14 years.

To all whom it may concern:

Be it known that I, EDWARD CLIFF, a citizen of the United States, residing at Newark, in the county of Essex and State of New Jersey, have invented and produced a new and original Design for an End Disk for Hose-Reels, of which the following is a specification, reference being had to the accompanying drawings, forming a part thereof, and in which—

10 Figure 1 is a side elevation of an end disk bearing and incorporating my design. Fig. 2 is a section of same on the dotted line 2 2 of Fig. 1, and Fig. 3 is a detached section through one part of same on the dotted line 15 3 3 of Fig. 1.

The leading feature of my design consists in the form and configuration of the end disk, substantially as shown in the drawings.

In the drawings, A designates the end disk 20 as a whole, the said disk comprising the rim

portion B, the body portion C, and spokes D. The rim portion B has the annular beading E at its outer edges, and said rim B has merged into it the spokes D, which radiate from the body portion C, as shown. The 25 spokes D have rounded outer surfaces and at their inner ends merge into the said body portion C. The surfaces of the spokes D present the appearance of being in strong relief, as shown in Figs. 1 and 3, and the disk 30 as a whole is of the character illustrated.

What I claim is—

The design for an end disk for hose-reels, substantially as shown and described.

Signed at New York, in the county and State 35 of New York, this 10th day of February, 1900.

EDWARD CLIFF.
